HOOD LATCH

Filed Nov. 7, 1927

Inventor
Melvin G. Baker
by Parker + Carter
Attorneys.

UNITED STATES PATENT OFFICE

MELVIN G. BAKER, OF CHICAGO, ILLINOIS, ASSIGNOR TO CHICAGO FORGING & MANUFACTURING COMPANY, OF CHICAGO, ILLINOIS, A CORPORATION OF ILLINOIS

HOOD LATCH

Application filed November 7, 1927. Serial No. 231,478.

My invention relates to a latching device and particularly to a device intended for use as an automobile hood latch. One object of the invention is to provide a hood latch, which, while serving to hold the hood down and closed, will also force the hood inwardly against its abutment and will thus hold it against rattling. Another object is the provision of a latch of the type above mentioned, which will be cheap and easy to manufacture, simple and durable in construction and strong and sturdy in use.

Other objects will appear from time to time in the course of the specification and claims.

I illustrate my invention more or less diagrammatically in the accompanying drawings, wherein—

Figure 1 is a vertical section through an automobile hood showing my hood latch in locking position;

Figure 2 is a plan view of the structure as shown in Figure 1;

Figure 3 is a vertical section through the latch stem and handle and head before being assembled;

Figure 4 is a section on the line 4—4 of Figure 3;

Figure 5 is a vertical section similar to Figure 3 showing parts assembled;

Figure 6 is a section on the line 6—6 of Figure 5;

Figure 7 is a front elevation of the upper portion of the sleeve;

Figure 8 is a side elevation of the sleeve;

Figure 9 is a section on the line 9—9 of Figure 7;

Figure 10 is a side elevation of the handle partly in section; and

Figure 11 is a vertical section of a variant form.

Like parts are indicated by like symbols throughout the specification and drawings.

A is a portion of an automobile frame, to which may be secured an upstanding rib or abutment member A¹, against which abuts the lower edge B¹ of the hood B when the hood is closed. Fastened to the hood B is a member generally designated as B², which includes a downwardly and outwardly inclined cam portion B³, upwardly and outwardly in-

clined prongs B⁴ separated, for example, by the notch B⁵, a central portion B⁶ which is secured to the hood B, and a downwardly and inwardly turned bottom portion B⁷. B⁸ are any suitable securing members.

C is any suitable shaft or pin terminating at the bottom in the square beveled head C¹. C² generally indicates a base member having a frame engaging securing portion C³, through which may pass any suitable securing member C⁴, and the intermediate raised portion formed by the upwardly and inwardly inclined top portion C⁵ and the generally vertical side walls C⁶. C⁷ is a concave, generally spherical flange surrounding the aperture C⁸, through which passes the pin C.

The latch body proper consists of the cylindrical member D, herein shown as rolled from a single blank and with the single axial seam D¹. The bottom of the cylinder may be formed in any suitable manner to retain the abutment below described. I illustrate the cylinder as being inwardly crimped as at D² to secure the washer D³ which is loose on the shaft C. D⁴ is a washer secured to the upper end of the pin C and D⁵ indicates a coil spring compressed between the two washers. The tendency of such spring is therefore to draw the cylinder D downwardly along the stem C.

The cylindrical member or seamed tube D is formed with indentations or apertures in its upper portion. I illustrate the horizontal notches or apertures E E¹ situated a slight distance from the top of the tube. The tube may, if desired, be formed with the inwardly turned flanges E². It will be realized that the top of the tube may be formed in a variety of different ways, it being essential that some aperture or indentation or inwardly off-set portion be provided.

G indicates generally a handle member which includes a finger engaging portion G¹ projecting from one side, and the T lug G², with the cross-bar G³, extending from the other. The intermediate portion G⁴ is provided with a downwardly projecting cylindrical flange G⁵ centrally apertured as at G⁶ to receive the upper end of the tube D. Prior to the assembly and completion of the latch

the portion G^5 is provided with outwardly projecting lugs or extensions of material overlying or aligned with the apertures E E^1 . In assembling the latch any suitable arbor G^7 may be introduced within the tube and, when the handle member G is in position the lugs or extensions G^6 are placed between squeezing jaws G^7 and are subjected to pressure sufficient to flow the metal of the handle into the opposed indentations or apertures of the tube. The result is a peculiarly complete and permanent attachment of handle to tube, the connection being only severable by the destruction of the handle member or the collapse of the tube. The collapse of the tube is particularly difficult, and in practice is not likely to take place, since the end of the tube is both protected and reinforced by the sturdy surrounding portion G^5 of the handle. G^{10} indicates any suitable lugs or lug member opposed to the cam B^2 on the hood.

In the operation of the latch it will be understood that when the T lug is between the members B^4 in the notch B^5 , the outward movement of the latch away from the hood is prevented. As the spring D^5 draws the cylinder D downwardly along the pin C the lugs G^{10} are opposed to the cam B^2 and to the downward locking movement of the latch is added the resultant lateral thrust against the hood.

In Figure 11 I have shown the cylinder D having the indentation H , instead of slots.

In particular it will be realized that where in the claims I employ the term "aperture" I wish to be understood as meaning not merely an aperture completely through the tube, but any indentation or off-setting of the tube or the tube surface which will provide an equivalent space into which the metal of the handle may flow.

Whereas I have illustrated means for forcing cold metal into the indentations or apertures of the member D it will be realized that I may obtain an equivalent result by positioning the tube B in a mold and pouring hot metal about it, thereby causing the metal to flow into the apertures and thus to form a permanent engagement with the tube equivalent to that formed by the flowing of cold metal into the tube.

Whereas I have described and shown my invention as employed in the application of a handle to the tube or stem of a hood latch, it will be realized that I do not wish to be limited to any such use. My invention may be employed in any case where a metallic member is being applied to one or both ends of a tube or bar.

I claim:

1. In a hood latch, a tubular latch body, an aperture in the upper end of said tubular body, a handle member surrounding the upper end of said tubular body and overlying

said aperture, the metal of said handle member penetrating said aperture.

2. In a hood latch, a tubular latch body of sheet metal stock, an aperture in the upper end of said body, a handle member surrounding the upper end of said body and overlying said aperture, the metal of said handle member penetrating said aperture. 70

3. In a hood latch, a tubular latch body of sheet metal stock, an aperture in the upper end of said body, a handle member surrounding the upper end of said body and overlying said aperture, the metal of said handle member penetrating said aperture, the metal of said handle member being of substantially 75 80 greater thickness than the latch body.

4. In a hood latch, a hollow cylindrical latch body having an aperture in the upper portion of the cylindrical side thereof, a handle member overlying the top of said cylinder and an extension thereof depending about and surrounding the upper end of the tubular body and overlying said aperture, the metal of said extension of the handle member penetrating said aperture. 85

5. In a hood latch, a hollow cylindrical latch body having a plurality of apertures in the upper portion of the cylindrical side thereof, a handle member overlying the top of said cylinder and an extension thereof depending about and surrounding the upper end of the tubular body and overlying said apertures, the metal of said extension of the handle member penetrating said apertures. 90 95

6. In a hood latch, a hollow cylindrical latch body having a plurality of diametrically opposed apertures in the upper portion of the cylindrical side thereof, a handle member overlying the top of said cylinder and an extension thereof depending about and surrounding the upper end of the tubular body and overlying said apertures, the metal of said extension of the handle member penetrating said apertures. 100 105

Signed at Chicago, county of Cook and State of Illinois, this 17th day of October, 1927. 110
